COMBINED COIN CONTAINER AND DISPENSER

George Luisa, South Country Road,
Brookhaven, N.Y. 11719

Filed Nov. 3, 1969, Ser. No. 19,885

Term of patent 7 years

Int. Cl. D20—99

U.S. Cl. D52—4

FIG. 1 is a perspective view of a combined coin container and dispenser showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and

FIG. 7 is a left side elevational view thereof.

I claim:

The ornamental design for a combined coin container and dispenser, substantially as shown.
